UNITED STATES PATENT OFFICE.

ROY C. BENNETT, OF HENDERSONVILLE, NORTH CAROLINA.

DESIGN FOR A TELEPHONE CABINET.

Application filed March 25, 1927. Serial No. 21,348. Term of patent 14 years.

To all whom it may concern:

Be it known that I, ROY C. BENNETT, a citizen of the United States, residing at Hendersonville, in the county of Henderson and State of North Carolina, have invented a new, original, and ornamental Design for a Telephone Cabinet, of which the following is a specification, reference being had to the accompanying drawing, forming part thereof.

I claim:

The ornamental design for a telephone cabinet, as shown.

ROY C. BENNETT.
